DESIGN FOR A BADGE

Frank de Ganahl, Riverton, N. J., assignor, by mesne assignments, to Kaiser Cargo, Inc., a corporation of California

Application March 13, 1943, Serial No. 109,751

Term of patent 14 years

To all whom it may concern:

Be it known that I, Frank de Ganahl, a citizen of the United States, residing at Riverton, in the county of Burlington and State of New Jersey,
have invented a new, original, and ornamental Design for a Badge, of which the following is a specification, reference being had to the accompanying drawing, forming a part thereof.

Figure 1 is a front view, and Figure 2 is a side view of a badge showing my new design.

I claim:
The ornamental design for a badge, as shown.

FRANK DE GANAHLL.
